DESIGN FOR A RADIATOR TRAP

Clifford J. Schlafman, Merchantville, N. J., assignor to Warren Webster & Company, Camden, N. J., a corporation of New Jersey

Application July 17, 1935, Serial No. 57,689

Term of patent 14 years

To all whom it may concern:

Be it known that I, Clifford J. Schlafman, a citizen of the United States, residing at Merchantville, in the county of Camden and State of New Jersey, have invented a new, original, and ornamental Design for a Radiator Trap, of which the following is a specification, reference being had to the accompanying drawing, forming a part thereof.

Fig. 1 is a perspective view of the radiator trap, showing my new design, and

Fig. 2 is a top plan view of the same.

I claim:

The ornamental design for a radiator trap, as shown.

In witness whereof, I have hereunto subscribed my name.

CLIFFORD J. SCHLAFMAN.
